UNITED STATES PATENT OFFICE.

DAVID FRANK, OF BROOKLYN, NEW YORK, ASSIGNOR OF ONE-HALF TO
JOHN TROUNSTINE, OF NEW YORK, N. Y.

DESIGN FOR AN END FRAME FOR BEDSTEADS.

SPECIFICATION forming part of Design No. 34,194, dated March 5, 1901.

Application filed February 9, 1901. Serial No. 46,743. Term of patent 7 years.

To all whom it may concern:

Be it known that I, DAVID FRANK, a citizen of the United States, residing at Brooklyn, Kings county, New York, have invented and produced a new and original Design for an End Frame for Bedsteads, of which the following is a specification, reference being had to the accompanying drawings, forming a part thereof, and in which—

10 Figure 1 is a front elevation of an end frame for bedsteads bearing and incorporating my design, and Fig. 2 is an end view of same.

The leading features of my design consist of the form and ornamental configuration of the end frame, substantially as shown.

15 In the drawings, A A designate the corner posts of the end frame, which posts have their ornate upper ends B (not novel herein) connected by the top rail or rod C. The customary transverse upper and lower rods are let-

tered D E, and intermediate these rods are the vertical rods F.

The distinctive part of the present design is located between the upper rod D and top rail C and comprises the central oval panel 25 G, the scroll-rod H within said panel, the scrolls I I at the ends of said panel, and the said top rail C, the whole being substantially as shown.

20 What I claim is—

The design for an end frame for bedsteads, substantially as shown and described.

Signed at Brooklyn, in the county of Kings and State of New York, this 5th day of February, 1901.

DAVID FRANK.
